UNITED STATES PATENT OFFICE.

MARTIN STAGUHN, OF MILWAUKEE, WISCONSIN.

PLOW.

SPECIFICATION forming part of Letters Patent No. 694,689, dated March 4, 1902.

Application filed October 30, 1901. Serial No. 80,492. (No model.)

To all whom it may concern:

Be it known that I, MARTIN STAGUHN, residing at Milwaukee, in the county of Milwaukee and State of Wisconsin, have invented a new and useful Improvement in Plows, of which the following is a description, reference being had to the accompanying drawings, which are a part of this specification.

My invention consists of the improved plow, its parts and combinations of parts, as herein described and claimed, or the equivalents thereof.

In the drawings, Figure 1 is a side elevation of my improved plow. Fig. 2 is a top plan view of the improved plow. Fig. 3 is a section of the plow on line 3 3 of Fig. 1 looking toward the left.

My improved plow is advisably constructed entirely of metal and preferably of steel, with the single exception that the handles may be made of wood.

In the drawings 5 is the beam which is constructed advisably of a bar of steel, the rear extremity of which is bent downwardly 25 forming a leg 6 and in the plow extends to the bottom or horizontal plane of the lowest edge of the landside or what in this plow is more properly demonstrated a runner. This downwardly-extending leg 6 is offset laterally at 7 toward the moldboard. A member 8 which I denominate the knee is a metal strap secured advisably by rivets, to the beam 5 at a short distance in front of the leg 6 and extends substantially vertically 30 therefrom downwardly and is secured advisably by a rivet to the runner 9. The runner 9 is fastened to the lower extremity of the leg 6 and also to the knee 8 and projects forwardly therefrom in a substantially horizontal 35 direction or parallel with the beam, its lower edge being inclined upwardly slightly near the front end. The main share 10 is secured detachably on the front end of the runner 9 by means of bolts or screws, the upper 40 edge of the runner near its front end being provided with a laterally-extending flange therefor, on which the share rests and through which the bolts or screws pass. The share 45 10 is in an elongated triangular form common in shares, the point being toward the front and the base toward the rear. Its form and disposition are such as to adapt it to cut along

its front outer edge and on its upper surface to lift the earth in which the plow is drawn. Extending rearwardly from the share 10 there 55 is a moldboard 11, which consists of a strap of metal of narrower width than the rear or base end of the share 10 and of equal width throughout its entire length, the strap being twisted or warped, so that while its front end 60 is approximately in a flat horizontal plane its rear end is in a substantially vertical plane. The rear end of this moldboard is held in position by a brace 12, secured to the moldboard and to the lower end of the leg 6, conveniently 65 by means of a bolt passing through the runner 9, the leg 6, and the brace 12.

An auxiliary share 13, of triangular form, having its point toward the front and its base toward the rear, with an upwardly and laterally projecting sharpened edge, is mounted rigidly on a shank 14, which projects rearwardly from the share and in the direction of its lower straight edge. This shank 14 is offset at 15 and is secured at its rear end to the leg 6 above the offset 7 and to the knee 8 medially, the shank bearing against a medial portion 16 of the knee 8, which medial portion is offset away from the moldboard and from the vertical plane of the beam. The shank 14 is secured detachably to the leg 6 and to the knee 8 by means of clips 17, that pass around the shank and go through the leg and the knee and are provided with nuts turning on the legs of the clips. By this means the shank is secured firmly but releasably in place on the knee and the leg. An auxiliary moldboard 18, consisting of a strip of metal 85 advisably thinner, lighter, and narrower than the moldboard 11, is secured at its front end rigidly to the auxiliary share 13 and at its rear end is secured by a brace 19 to the leg 6, screws or bolts with nuts being employed to secure the brace to the moldboard and the leg, so as to make the same detachable. The construction and disposition of the parts are such that the auxiliary share 13 is in an oblique position outwardly and upwardly away from the moldboard 11 and also away from the vertical plane of the beam 5. This disposition of the auxiliary share 13 is best illustrated in Fig. 2. The auxiliary moldboard 18 extends rearwardly and slightly upwardly from the auxiliary share 13. The auxiliary 90 95 100

share 13 and the moldboard 18 are located at a distance from but parallel with the inner and upper edge or landside edge of the share 10 and the moldboard 11. The landside or 5 runner 9 is so disposed that the plane of its width is substantially vertical, but in a plane slightly on the moldboard side of the vertical plane of the beam.

Handle-posts 20 20, also of metal straps, are 10 provided, which straps are placed against each other at and near their lower ends and are secured to the runner 9 and the leg 6 in an upwardly and rearwardly extending direction by means of bolts or rivets. Above the point 15 at which these posts are secured to the leg they separate from each other and at their upper ends are provided with tangs on which are placed wood handles 21 21', the handle 21 being advisably so disposed as to project rearwardly horizontally, while the handle 21' projects laterally horizontally. The handles are secured to each other by a metal round 22 and are strengthened by brace-rods 23 23, secured to the handles at the round 22 and to the beam 25 at the junction of the knee 8 therewith.

For hauling the plow along it is provided with a rod draw-bar 24, which at its rear end is hooked into the knee 8 and at the front end passes freely through a guide 25. The guide 30 25 is adjustable vertically in slots therefor through the ends of a clevis 26, which is provided with a set-screw 27, turning through the bend of the clevis against the front surface of a laterally-elongated and slotted head 35 28, fixed on the front extremity of the beam 5. By this construction both lateral and vertical adjustment of the draw-bar at the front end of the beam are provided for.

What I claim as my invention is—

40 1. A plow comprising a beam the rear portion of which is turned down forming a leg,

a vertically-disposed knee, a landside secured to the leg and to the knee, a main share and a main moldboard secured to each other and to the runner and the leg, and an auxiliary 45 share and moldboard separate from and above the main share and moldboard and secured detachably to the leg and the knee.

2. In a plow, a beam, a main share and a moldboard disposed at the right of the vertical plane of the beam, and an auxiliary share 50 provided with an auxiliary moldboard, the auxiliary share being mounted in the plow above and at a distance from the main share and at the left of and in an oblique plane upwardly away from the vertical plane of the beam.

3. In a plow, a beam provided with a leg offset laterally, a landside secured to and projecting forwardly from the leg, a knee secured terminally to the beam and the landside and having a medial portion offset laterally, and an auxiliary share and moldboard provided with a rearwardly-extending shank and means securing the shank detachably to 65 the leg and to the knee.

4. In a plow, a steel-strap horizontally-disposed beam turned down at its rear end forming a vertically-disposed leg, a steel-strap landside secured to the leg, a steel-strap knee 70 secured to the beam and to the landside, steel-strap handle-posts secured to the landside and to the leg, and a share or shares with a moldboard mounted on the parts aforesaid forming the frame of the plow.

In testimony whereof I affix my signature in presence of two witnesses.

MARTIN STAGUHN.
